UNITED STATES PATENT OFFICE.

CARL C. KUSTERER, OF GRAND RAPIDS, MICHIGAN.

CHEST.

Application filed May 25, 1927. Serial No. 194,088.

The main object of this invention is to provide a chest comprising trays or sections supported thereby, making the entire storage space of the receptacle conveniently available and accessible.

Objects relating to details and economies of construction will appear from the detailed description to follow. The invention is defined in the claims.

10 A structure which is a preferred embodiment of my invention is illustrated in the accompanying drawing, in which:

Fig. 1 is a perspective view of a chest, having corner posts and legs, embodying the features of my invention, a portion of the side wall being broken away to show details of construction.

Fig. 2 is an enlarged detail perspective view of the upper portion of said chest, with the lid raised and the left hand tray fully extended and the right hand tray in mid position, the parallel link supports being indicated by dotted lines.

Fig. 3 is a detail cross sectional elevation view taken on plane of line 3—3 of Fig. 1.

Fig. 4 is a diagrammatic detail of a modified form of the chest.

The parts of the drawings will be identified by their numerals of reference which are the same in all the views.

1 is the main body of the chest. 2 are the corner posts thereof extended downwardly into legs 3. 4 is the lid hinged in any suitable way and provided with the usual stop connection and support 5, centrally located to occupy a space between the inner ends of the trays. 6 are the ends of the chest body which extend about half way to the top of the chest, leaving an open space at each end which is occupied by the trays 7. The end 8 of each tray 7 forms the upper part of the end of the chest when the same is in closed position. Each tray is carried by two pairs of parallel links 9, 9, pivoted at 91, 91 inside and toward the bottom of the main body of the chest and at the upper end at 92, 92 to the sides of the tray 7 toward the inner part thereof. The outer ends 8 of the tray extend laterally into projecting ribs 81. A guide rib 71 is at the bottom of the outer portion of the tray at each side. Within the side walls of the chest toward the

top are guiding ribs 11 disposed at a point above the swinging path of the outer ends of the parallel links 9 which serve to guide 55 the trays 7 to place and prevent marring of their sides.

From this description it will be seen that on raising the lid 4 of the chest the trays 7 can be moved outwardly at each end, exposing the contents of the bottom of the main body of the chest and supporting the trays at each side in accessible position, thus making the whole contents of the chest very conveniently accessible.

65 The chest can be given a fancy form, as seen in Fig. 4, where the ends, in place of being perpendicular, are oblique, with a corresponding form of the tray. The chest is available for simple box construction. I 70 have shown it in elaborate construction with corner posts and legs, to which it is especially well adapted.

I desire to claim the invention broadly and also in the specific form illustrated, as 75 indicated in the appended claims.

Having thus described my invention, what I claim as new and desire to secure by Letters Patent, is:

1. A chest structure with suitable corner posts, the main body of which is provided with end walls at the lower portion thereof only, trays fitting within the space above the ends of said chest, parallel links for supporting the same pivoted to the inside of the 80 main body and to the sides of the said tray, a guiding rib at the lower outer portion of each tray and a guide rib within the main body toward the top at each side, and a hinged lid for closing the same, as specified. 85 90

2. A chest structure, the main body of which is provided with end walls at the lower portion thereof only, trays fitting within the space above the ends of said chest, parallel links for supporting the same pivoted to the inside of the main body and to the sides of the said tray, a guiding rib at the lower outer portion of each tray and a guide rib within the main body toward the top at each side, and a hinged lid for closing 95 100 the same, as specified.

3. A chest structure, the main body of which is provided with end walls at the lower portion thereof only, trays fitting

within the space above the ends of said chest, parallel links for supporting the same pivoted to the inside of the main body and to the sides of the said tray, and a hinged lid for closing the same, as specified.

4. A chest structure, the main body of which is provided with end walls at the lower portion thereof only, trays fitting

within the space above the ends of said chest, means to support said trays when extended, 10 and a hinged lid for closing the same, as specified.

In witness whereof I have hereunto set my hand.

CARL C. KUSTERER.
